UNITED STATES PATENT OFFICE.

BURR B. BLOOD, OF CHICAGO, ILLINOIS, ASSIGNOR, BY MESNE ASSIGNMENTS, TO JEWEL PHONOPARTS COMPANY, OF CHICAGO, ILLINOIS, A CORPORATION OF ILLINOIS.

STOP DEVICE FOR PHONOGRAHS.

1,419,914.

Specification of Letters Patent. Patented June 20, 1922.

Application filed March 4, 1920. Serial No. 363,257.

To all whom it may concern:

Be it known that I, BURR B. BLOOD, a citizen of the United States, and a resident of Chicago, in the county of Cook and State 5 of Illinois, have invented certain new and useful Improvements in a Stop Device for Phonographs, of which the following is a description, reference being had to the accompanying drawing, which forms a part of 10 my specification.

My invention relates to an improvement in the stop device or brake for the disc-carrying turn-table of a phonograph and has for its object the provision of a construction 15 whereby rotation of the turn-table will be automatically arrested when the stylus of the sound-box has reached a predetermined point in its travel transversely of the record, namely in the innermost or one of the 20 concentric grooves adjacent the central portion of the disc.

The principal object of my invention is to provide a simple and inexpensive device for the purpose mentioned, which will be 25 positive in its operation and at the same time compensate for slight additional movement of the trip mechanism during the setting operation of, or any play that may occur in the device, without, however, necessitating any change in the general construction of the phonograph or its operating elements; my improved device permitting adjustments to take up any wear or slight inaccuracies that may occur in the device.

35 The invention and its purposes will be readily comprehended from the following detailed description of the accompanying drawings, wherein:—

Figure 1 is a plan view of my improved 40 stop device or brake and the co-operating portions of a phonograph, namely portions of a turn-table and tone-arm; the latter being shown in dotted lines.

Figure 2 is a detail view of a portion of 45 the trip element, looking at the bottom.

Figure 3 is a detail sectional view, taken on the line 3—3 of Figure 2, looking in the direction of the arrows.

Figure 4 is a detail sectional view taken 50 on the line 4—4 of Figure 2 looking in the direction of the arrows.

My improved stop device or brake mechanism is intended to be secured at a proper point on the phonograph cabinet and beneath the turn-table which is partially shown 55

at 10 in Figure 1; the mechanism being secured beneath the turn-table 10 at a point adjacent to the peripheral flange of the turn-table and in proximity to the base or pivotal point of the tone-arm which is indicated 60 in dotted lines at 11.

The stop device or brake mechanism in the specific exemplification comprises a base-plate 12 of any suitable shape adapted to be secured in a suitable manner to the top 65 of the phonograph cabinet, as for example by screws which take through the apertures 13 in the base-plate.

Pivotedly secured to the base-plate 12 by means of the vertically disposed pivot 14, 70 is a segmental or arcuate latch member 15 adapted to oscillate in a horizontal plane; while the inner curved side of the member is provided at a suitable point with an off-set or notch 16 intended to receive the extended 75 portion or tip 17 of a brake-lever 18 which latter is pivotally secured at 19 to the base-plate 12. The brake-lever 18 is provided with an extension 20 shown terminating in an upstanding flange 21, apertured to receive or otherwise provided with suitable friction-producing means 22 which in reality constitutes the brake-shoe adapted to have engagement with the inner surface of the depending peripheral flange with which the 80 turn-tables 10 are usually provided. The lever 18 is formed so as to extend from beneath the turn-table and provide a handle-portion 23 to enable the operator to release the brake and place it in non-braking position.

The latch-lever or member 15, preferably somewhere near to its pivotal point 14, is provided with an upstanding lug 24 to which one end of a tension spring 25 is secured, 95 while the other end of the spring is secured to a similar lug 26 formed on the inner end of the brake-lever 18 disposed intermediate of the brake-lever pivotal point 19 and latch-member 15, whereby the brake-lever and the 100 latch-lever will both be placed under spring tension, which, of course, increases when the brake-lever is oscillated into non-braking position, namely into a position where the tip 17 of the brake-lever will be in engagement 105 with the off-set or notch 16 of the latch-member 15. The arcuate formation or curvature of latch-member 15 is substantially equivalent to the arc described by the inner end of brake-lever 18 which is held in sliding rela- 110

tion with the latch-member 15. The base-plate 12 is also preferably provided with a lug 27 which acts as a stop for the inner end of the brake-lever 18 against the pulling 5 action of spring 25.

The outer end of the latch-member 15 is provided with a bifurcated trip-member 28, the short arm whereof is intended to be engaged by a finger or hook 38 secured at a 10 suitable point to the tone-arm 11; while the long arm of the bifurcated trip-member 28 permits the operator to adjust the trip-member 28 about its pivotal point 29 on the end of the latch-member 15, so as to bring the 15 short arm of member 28 into contact with the finger or hook 38 during the setting of the device.

The trip-member at the base adjacent the pivotal point is provided with a cut-away 20 portion or socket 30 to receive the lug or bent end 31 of a washer-member 32 which is clamped intermediate of the trip-member 28 and latch-member 15. The pivotal point 29 is so formed that the washer-member 32 will 25 be frictionally held against the end of latch-member 15 by the pivot 29, which latter may be somewhat in the nature of a rivet, and firmly clamps washer-member 32 by means of the sleeve or hub portion 33 which is pref- 30 erably formed integral with washer-member 32; the outer end of the sleeve or hub-portion 33 being shown offset or swaged so as to frictionally clamp the washer-member 32 to latch-member 15, while at the same time 35 enabling the washer 32 to be rotated in the end of latch-member 15 through the application of sufficient force, manually applied, to the long arm of the trip-member 28 which latter is more or less free on the rivet or pivot 40 member 29. The cut-away portion or slot 30 in trip-member 28 is of width greater than the width of the lug or turned end 31 of washer-member 32, to allow slight play be- 45 tween the trip-member 28 and the turned end or lug 31 of washer-member 32. The play between the trip-member 28 and latch-member 15 just referred to is intended to be com- 50 mensurate with and adapted to compensate for the slight movement of latch-member 15 toward the brake-lever 18 during the setting 55 of the device, namely, when the tip 17 of the brake-lever enters the notch 16 of latch-member 15.

In practice, the stop device or brake mech- 55 anism is adjusted to the point where it is desired that the mechanism shall automatically operate while the brake-lever is still in braking relation with the turn-table, at which time the tone-arm with its attached 60 sound-box is swung toward the groove of the record provided with the indentations where further operation of the phonograph is to cease. With the tone-arm in the position just mentioned, namely with the stylus of the 65 sound-box in the desired groove, the long

arm of trip-member 28 is grasped by the operator and forcibly moved about the pivot point 29 so as to bring the short arm of trip-member 28 into contact with the depending hook or finger 38 on the tone-arm, there- 70 by placing the mechanism in condition to be automatically tripped when the tone-arm again reaches this point during its travel transversely of the record, which, of course, is subsequent to the releasing of the turn- 75 table through proper manipulation of the brake-lever and after the tone-arm has been again swung toward the outer groove of the record, which latter action has moved the depending finger 38 out of contact with the 80 short arm of the trip-member 28. The move- 85 ment of the brake-lever 18 about its pivotal point 19 into non-braking position where the inner end of the brake-lever engages the notch 16, allows latch-member 15, with the 90 trip-member 28, to have slight movement in a direction toward brake-lever 18 and there- 95 fore beyond the desired point where the de- 100 vice was set for tripping operation; this slight movement usually amounting to a difference of one or more grooves on the record, so that the brake mechanism would ordi- 105 narily be actuated before it reaches the point where it is desired to discontinue the re- 110 production. It is quite important, there- 115 fore, that the play between the trip-member 12 and the latch-member 15 be substantially 120 equivalent to or proportionate to the amount of movement on the part of latch-member 15 induced through the action of spring 25 when 125 the tip 17 of brake-lever 18 enters the notch 16 of the latch-member.

It is understood, of course, that the relation between the trip-member 28 and latch- 130 member 15 must be such that contact of the 105 depending finger 38 on the tone-arm with the short-arm of the trip-member 28 will not cause movement of trip-member 28 in- 110 dependent of movement of latch-member 15; while at the same time this relation must 115 be such as to permit movement of trip-mem- 120 ber 28 relative to latch-member 15 through sufficient force applied by the operator.

In order to compensate for any inaccura- 125 cies in construction and also to compensate 115 for any wear intermediate of the end of brake-lever 18 and latch-lever 15, I provide a cam member 34 secured by means of a screw 35 to the trip-member 28, with the arcuate or cam surface of the member 34 120 disposed toward the turned end or lug 31 of washer-member 32. It is evident from this construction that the play between the turned end or lug 31 and the sides of the cut-away portion or slot 30 may be increased 125 by releasing the screw 35 and moving the arcuate end of the cam member 34, in clock- 130 wise direction in Figure 1, so as to take care of a greater amount of movement on the part of latch-member 15, resulting from 130

slight differences in construction, or wear between the members as previously described.

With my improved construction, the brake mechanism may be adjusted to such nicety as to bring about a braking relation between lever 18 and the turn-table at the exact point or desired groove on the record.

The base-plate 12, at what may be termed the rear side of the latch-member 15, is also preferably provided with a cam-plate or member 36 secured to the base-plate by means of a screw 37. The member 36 acts as a stop for the rearward movement or 15 oscillation of the latch-member 15, preventing the too far movement of brake-lever 18 beyond the notch 16; and this stop member or cam 36 also compensates for any slight differences in construction, by moving the 20 stop or cam 36 in clockwise direction in Figure 1, about the screw 37.

I am aware of the fact that stop devices or brake mechanisms for automatically arresting the turn-table of a phonograph and 25 employing latch-members provided with trip-members pivoted thereto, are not new; but the various stop devices or brake mechanisms heretofore employed do not permit of the accurate adjustment heretofore referred 30 to whereby a tripping of the stop device or brake mechanism is accomplished at the exact groove desired and it is to a stop device or brake mechanism adapted to accomplish this result, that my invention relates; and 35 while I have shown and described what I believe to be the best embodiment of the invention, alterations in certain details may be made without, however, departing from the spirit of the invention.

40 What I claim is:—

1. A device of the character described, comprising a brake-lever pivoted intermediate of its ends and adapted to have a portion thereof form braking relation with the 45 turn-table of a phonograph, one end of said lever constituting a handle-portion, a pivoted latch-member disposed along the path of movement of the inner end of the brake-lever which is adapted to have interlocking 50 engagement with an intermediate point of the latch-member, a spring secured to the inner end of the brake-lever and to said latch-member whereby they are held under tension, a trip-member pivotally secured at 55 the outer end of the latch-member, and means intermediate of the trip-member and latch-member whereby a frictional relation between the two members is provided after a predetermined degree of independent 60 movement by the trip-member.

2. A device of the character described, comprising, in combination with the turn-table and the tone-arm of a phonograph, the tone-arm being provided with a projection 65 adjacent to the base thereof, a brake-lever

pivoted intermediate of its ends and provided with a brake-shoe adapted to form braking engagement with the turn-table, the inner end of the lever terminating in a projection or lip, a pivoted latch-member disposed along the path of travel of the inner end of the brake-lever and provided on its adjacent side with a notch or off-set adapted to receive said projection or lip, a spring whereby the latch-member and brake-lever 70 are held under tension and the latch-member forced toward said lever when the brake-lever projection or lip registers with the notch or off-set, a trip-member pivotally secured to the outer end of the latch-member 75 and adapted to be engaged by the projection on the tone-arm, means intermediate of the trip-member and the latch-member whereby frictional relation between the two members is provided after a predetermined degree of 80 independent movement by the trip-member, and means whereby the degree of independent movement is made to correspond with the degree of movement of the latch-member 85 when the latter moves toward the brake-lever to engage with the projection or lip thereof.

3. A device of the character described, comprising, in combination with the turn-table and the tone-arm of a phonograph, the tone-arm being provided with a finger adjacent the base thereof, a brake-lever pivoted intermediate of its ends and having a turn-table engaging portion, the inner end of the lever terminating in a projection or 90 lip, a latch-member disposed along the path of travel of the inner end of the brake-lever and provided with a notch or off-set to receive the projection or lip, a spring whereby the latch-member and brake-lever are held 95 under tension and the latch-member forced toward the lever when said projection or lip registers with the notch or off-set, a trip-member pivotally secured to the outer end of the latch-member and adapted to be engaged by the finger secured to the tone-arm, the trip-member being provided with a socket adjacent the pivoted end thereof, and means intermediate of the trip-member and the latch-member, with a portion of the 100 means disposed in said socket, whereby independent movement of the trip-member is permitted until said portion of the means engages with the side walls of said socket 105 when a frictional relation between the two members is provided.

4. A device of the class described, comprising, in combination with the turn-table and the tone-arm of a phonograph, the tone-arm being provided with a projection, a 110 brake-lever pivoted intermediate of its ends and provided with a brake-shoe adapted to engage with the turn-table, a pivoted latch-member disposed along the path of movement of the inner end of the brake-lever and 115 120 125 130

adapted to have latching engagement therewith, a spring whereby the latch-member and the brake-lever are held under tension, a trip-member pivotally secured to the outer 5 end of the latch-member and adapted to be engaged by the projection on the tone-arm, means, intermediate of the trip-member and latch-member, whereby frictional relation between the two members is provided after 10 a predetermined degree of independent movement by the trip-member, and adjustable means whereby the degree of independent movement may be regulated.

5. A device of the character described, 15 comprising, in combination with the turn-table and the tone-arm of a phonograph, the tone-arm being provided with a finger adjacent the base thereof, a brake-lever pivoted intermediate of its ends and having a turn-table 20 engaging portion, a pivoted arcuate latch-member disposed about the path of travel of the inner end of said lever and provided with a notch or off-set adapted to receive the end of said lever, a spring secured 25 to the inner end of the lever and to said latch-member whereby the lever and member are held under tension and the latch-member forced toward the lever when the inner end thereof registers with said notch 30 or off-set, a trip-member pivotally secured to the outer end of the latch-member and adapted to be engaged by the finger on the tone-arm, means intermediate of the trip-member and the latch-member whereby frictional 35 relation between the two members is provided after a predetermined degree of independent movement by the trip-member, and adjustable means whereby the degree of oscillatory movement of the latch-member 40 in a direction away from the inner end of the brake-lever is controlled.

6. A device of the class described, comprising, in combination with the turn-table and the tone-arm of a phonograph, the tone-arm being provided with a projecting finger adjacent the base thereof, a brake-lever pivoted intermediate of its ends and having a turn-table engaging portion, a pivoted arcuate latch-member disposed about the 45 path of travel of the inner end of said lever and provided on its inner side with a notch or off-set adapted to receive the inner end of said lever, a spring secured to the inner end of said lever and to said latch-member 50 whereby the two are held under tension and the latch-member forced toward the lever when the inner end of the latter registers with said notch or off-set, a bifurcated trip-member pivotally secured to the outer end 55 of the latch-member, one bifurcation being adapted to be grasped by the operator for adjusting the trip-member, while the other bifurcation is adapted to be engaged by the finger on the tone-arm when the latter 60 approaches the predetermined point on the

record, means intermediate of the trip-member and the latch-member whereby frictional relation between the two members is provided after a predetermined degree of independent movement by the trip-member, 70 means whereby the degree of independent movement may be regulated to be commensurate with the degree of movement of the latch-member toward the lever when the end of the latter registers with the notch or 75 off-set in the latch-member, and adjustable means whereby the degree of oscillatory movement of the latch-member in a direction away from the inner end of the brake-lever is controlled.

7. A device of the character described, comprising a base-plate, a brake-lever pivotally secured intermediate of its ends to the base-plate and provided with a brake-shoe, an arcuate latch-member pivoted at one end 80 to the base-plate and disposed about the inner end of the brake-lever, the latch-member and the inner end of said lever in its travel describing the arcs of substantially concentric circles, the concaved side of the latch-member being provided with a notch or off-set adapted to receive the inner end of the lever, a spring secured to the inner end of the lever and to the latch-member so as to maintain them under tension and force the 85 latch-member toward the lever when the inner end of the latter registers with the notch or off-set, a trip-member pivotally secured to the free end of the latch-member, said trip-member being provided with a slot, means 90 intermediate of the trip-member and the latch-member and provided with a projection extending into said slot, whereby independent movement is permitted the trip-member until the projection reaches the end 95 of said slot when frictional relation between the two members is provided and the two members made to move together, and means 100 whereby the extent of independent movement of the trip-member may be regulated. 105

8. A device of the character described, comprising a brake-lever pivoted intermediate of its ends, an arcuate latch-member pivoted at one end and disposed about the inner end of the brake-lever, the inner or concaved side of the latch-member being provided with a notch or off-set adapted to receive the inner end of the brake-lever to retain the latter in non-braking position, a spring secured to the inner end of the brake-lever and to the latch-member so as to maintain them under tension and to force the 110 latch-member toward the brake-lever when the inner end of the latter is brought to register with said notch or off-set, a trip-member pivotally secured to the free end of the latch-member, means intermediate of the trip-member and the latch-member whereby frictional relation between the two members is provided after a predetermined degree of 115 120 125 130

movement by the trip-member, said means comprising a portion disposed into the path of the trip-member, adapted to be engaged thereby and the latch-member caused to move 5 with the trip-member, and adjustable means whereby the moment of operative engagement between said last mentioned portion and the trip-member may be controlled.

9. A device of the class described, comprising a base-plate, a brake-lever pivoted intermediate of its ends on said base-plate and provided with a braking portion or shoe, an arcuate latch-member pivoted at one end on said base-plate and disposed 10 about the inner end of the brake-lever, the inner concaved side of the latch member being provided with a notch or off-set adapted to receive the inner end of the brake-lever to retain the latter in non-braking position, a 15 spring whereby the brake-lever and latch-member are placed under tension and the latter forced toward the brake-lever when

the inner end thereof is brought to register with said notch or off-set, a trip-member pivotally secured to the free end of the latch-member, means intermediate of the trip-member and the latch-member whereby frictional relation between the two members is provided at a predetermined moment in the oscillation of the trip-member, said means 25 comprising a portion disposed into the path of the trip-member to be engaged thereby, whereby the latch-member is caused to move with the trip-member, and means whereby the moment of operative relation between 30 the trip-member and the latch-member may be determined and substantially correspond with the degree of movement of the latch-member toward the inner end of the brake-lever.
